UNITED STATES PATENT OFFICE.

NICHOLAS DEDRICK, OF MANITOWOC, WISCONSIN.

DESIGN FOR A SPOON-BOWL.

47,132.

Specification for Design.

Patented Mar. 23, 1915.

Application filed November 6, 1914. Serial No. 870,711. Term of patent 14 years.

To all whom it may concern:

Be it known that I, NICHOLAS DEDRICK, a citizen of the United States, residing at Manitowoc, in the county of Manitowoc and State of Wisconsin, have invented a new, original, and ornamental Design for Spoon-Bowls, of which the following is a specification, reference being had to the accompanying drawings, forming part thereof.

In the drawings Figure 1 is a plan view of a spoon showing my new design; Fig. 2, a sectional elevation of the same, the same being indicated by line 2—2 of Fig. 1, and Fig. 3, a cross-section of the spoon bowl, the

section being indicated by line 3—3 of Fig. 1 looking in the direction of the arrows.

I claim:

The ornamental design for a spoon bowl, as shown.

In testimony that I claim the foregoing I have hereunto set my hand at Manitowoc, in the county of Manitowoc and State of Wisconsin, in the presence of two witnesses.

NICHOLAS DEDRICK.
